METHOD OF SHOE MAKING

Fred Maccarone, Brooklyn, N. Y.

Application January 7, 1939, Serial No. 249,702

1 Claim. (Cl. 12—146)

The present invention relates to shoe making methods whereby shoes having a highly flexible ball portion and relatively stiffer shank and heel portions are produced.

5 A principal object of my invention is to provide shoes of the type mentioned in which a thin insole of any suitable material as leather, cardboard, fiber composition or the like which is perforated in its ball portion to produce a skeleton 10 rand having a feathered inner edge, has a shoe upper and possibly an inner sock lining lasted to the marginal portions of said insole, and a thin flat outsole applied over the lasted upper. The insole preferably is so applied to the last 15 that, in the finished shoe, the tapered feathering portion on the rand faces the bottom of the shoe. Thus sufficient space is provided between the insole and outsole in the marginal regions of said insole to accommodate the shoe upper and inner 20 lining which are lasted to said marginal regions of said insole. The feathering edge of the insole lies flush with the inner surface of the outsole and as a result, the net thickness of the composite sole in the major portion of the ball thereof is substantially that of the outsole member only. In 25 the other parts of the shoe, the net thickness of the composite sole is the sum of the thickness of the thin insole and thin outsole whose individual thicknesses are so chosen that the composite 30 thickness of the sole is suitable for the particular kind of shoe being made. A shoe embodying this structure has, as a result, a composite sole with a very flexible ball portion and relatively stiffer shank and heel portions. In addition such shoes 35 are markedly economical as to cost of materials and production and have a pleasing finished appearance.

Another principal object of this invention is to provide a method for and means of making insoles of thin independent stock and of using them 40 in the manufacture of shoes having specific added flexibility in the ball portions thereof over other types of shoes without detracting from the neat and accurate construction thereof and effecting economies in the net cost of manufacture 45 and without requiring the insoles and outsoles to have complementary interfitting parts.

Another object of this invention is to provide insoles of the type first described which are not 50 restricted as to material to leather split from an outsole, and which may be made of any suitable material.

Yet another object is to provide efficient comparatively inexpensive machinery for producing 55 insoles of the type desired.

A still further object of the invention is to provide a shoe and method of making the same which has a thinned ball portion constituting substantially the outsole only, is compact and strongly lasted and has the characteristic appearance of and increased flexibility over the now popular single sole type of shoe.

To the accomplishment of the foregoing and such other objects as may hereinafter appear, this invention comprises the novel shoe, the novel 10 method and novel combination and arrangement of parts hereinafter described and then sought to be defined in the appended claim, reference being had to the accompanying drawings forming part 15 hereof and which show, merely for the purposes of illustrative disclosure, preferred embodiments of my invention, it being expressly understood, however, that various changes may be made in practice within the scope of the appended claim without digressing from my inventive idea.

In the drawings in which similar reference characters denote corresponding parts:

Fig. 1 is a longitudinal sectional elevation of apparatus adapted to produce my novel insoles and particularly adapted to cut or skive away the central part of the ball portions of such insoles;

Fig. 1a is a fragmentary detail view of the insole deforming and cutting portion of the apparatus of Fig. 1 illustrating the same during the cutting or skiving of the insole;

Fig. 2 is a top plan view of the device of Fig. 1;

Fig. 3 is a section along line 3—3 of Fig. 2 viewed in the direction of the arrows;

Fig. 4 is a view similar to Fig. 3 illustrating a modified means and method of removing the central ball portion of an insole;

Fig. 4a is a reduced size perspective view of the modified die block used and shown in section in Fig. 4;

Fig. 5 is a diagrammatic sectional view illustrating a further modified form of apparatus for removing said central ball portion;

Fig. 6 illustrates in perspective the ball and shank portions of an insole prepared with the device of Figs. 1—3 inclusive and the portion cut away therefrom.

Fig. 7 illustrates in perspective the ball and shank portions of an insole prepared with the device of Fig. 4 and the portions cut away therefrom; and

Fig. 8 is a cross section of the forepart of a shoe embodying the sole structure of my invention.

A shoe embodying the sole structure of the present invention comprises generally an upper

10, an inner lining or linings 11, a thin insole 12 of any suitable material such as leather, cardboard, fiber composition or the like and a thin leather outsole 13. The insole comprises the usual integral heel portion (not shown), shank portion 14 and ball portion, the said ball portion having a central opening P therein defining a continuous marginal rand 15 extending from the front of one side of the shank around 10 the toe and to the front of the opposite side of the shank. This rand tapers from one face of the rand to a feather edge 15' in the opposite face of said rand. In thickness the insole should preferably not exceed two or three irons. The 15 flat faced outsole 13 is rounded in usual form to the shoe shape, corresponding in general outline to the outline of the insole. In thickness the outsole can be of any suitable thickness.

The insole besides rounding requires a cutting 20 or skiving out of the central ball portion to produce the rand forepart 15 with its feather edge 15'. Apparatus for effecting this result in several ways is shown in Figs. 1-4 inclusive.

Referring first to Figs. 1-3 inclusive, 30 denotes 25 a frame having a top 31. This top is provided with a longitudinally extending opening 32. A tiltable table 33 is supported in the opening 32 on suitable bearings 34 journaled to the axle 35 which is mounted crosswise in the side walls 30' 30 of the frame 30.

Intermediate its ends on its top face the table 33 has a depression or recess 38 shown in the present embodiment as rectangular in shape. A die block 40 of metal or other suitable substance 35 is removably mounted in the recess. This block has an island like projection which in plan has a shape corresponding to that of the portion it is desired to cut from the ball of the insole member and in section has a thickened central 40 portion 40' and tapering marginal portions 40''. The outer edges of the marginal portions are adapted to lie flush with the upper surface of the table top and the thickened central portion projects above the table surface as an island like 45 projection shaped to correspond to the outline of the cut out ball portion of the insole a distance suitably arranged to insure the cutting out of the desired section of the ball portion in a manner to be presently described.

50 A guide member 45 which is adjustable longitudinally of the table 33 is provided on its top surface near its rear edge. This member is adapted to be locked in any adjusted position by the set screws 46 operating through the slots 55 47 in said member. The adjustability of this block is important to allow for operation on insoles of differing shoe sizes as will be presently described.

60 A second guide 48 arranged longitudinally of the table 33 at one side thereof serves together with the guide 45 to position the insole to be cut accurately with respect to the table with the central part of the ball portion in position over the die block 40.

65 A reciprocating carriage frame 50 slideable over the top 31 and a portion of the table 33 in longitudinal direction thereof is provided. This frame has laterally extending guide flanges 55 on opposite sides which are adapted to slide in 70 guide grooves 56 provided in guide rails 57 which latter are suitably attached to said top 31 on opposite longitudinal sides.

The rear end of the frame 50 is provided on each side with a lateral inwardly extending projection 60. Suitably mounted on said projec-

tions 60 on the bottoms thereof is a knife 65 whose bottom face is adapted to extend substantially parallel with the top 31 and to move thereover in longitudinal direction of the top when the frame 50 is reciprocated. The cutting edge 5 65' of the said knife, is preferably formed by beveling the said knife downwardly and forwardly from its top surface as at 65''. Thus, the bottom face of the knife and its cutting edge extend parallel to said top and are spaced therefrom a distance substantially equal to that of the height of projection 40' of the die block so that when the frame 50 is reciprocated the knife will clear the said projection but slidably engage it with its bottom face. 15

A press roller 70 is removably supported in well known manner on a rotatable shaft 71 carried in bearings 72 provided on opposite longitudinal sides of the frame 50. This roller is provided with a depression or matrix 75 developed 20 on its surface and corresponding in outline with the projection 40' of the die block 40, so that as said roller moves over the die block, the projecting portions thereof extend into the complementary portions of the said depression. Suitable spacing between the roller surfaces and the die block are provided to allow for the thickness of the insole material from which the central ball portion is to be removed.

A pinion 78 is keyed to the roller 70 and adapted 30 to move over a rack bar 79 which extends longitudinally of the top 31 and is supported thereon. An adjusting screw 80 or the like threaded in a projection 81 of the top 31 and attached to one end of the rack at 82 permits 35 longitudinal adjustment of said rack to adapt the device for operating on different shoe sizes of insoles. The lock nut 83 serves to lock said screw in any adjusted position.

Provision of the said pinion 78 and rack bar 40 79 causes rotation of the roller 70 as the frame 50 is reciprocally moved.

Reciprocal motion of the frame may be effected as follows:

Pivotedly supported at 85' on the forward end 45 of the frame 50 is a link bar 85 whose free end pivotally engages at 85'' one end of a crank lever 86. The opposite end of said crank lever 86 is rotatably supported on a pivot shaft 87 carried by the frame 30. Intermediate its ends said lever 50 is provided with a lateral extension 88 to which a rotatable cam following roller 89 is attached.

A suitably driven shaft 90 is supported in frame 30 and has keyed thereto a cam 91 with which the cam roller 89 engages. This cam is so designed as to draw the frame 50 forwardly over the top 31 during the cutting stroke and permit its quick return to initial position after completion of said cutting stroke and to permit the frame to remain in idle initial position for a predetermined 60 amount. The operation of the cam may be described as single cycle, each cycle consisting of a cutting period, a return period and an idling period. The time of the three periods are suitably allocated and proportioned to permit the insertion of a fresh insole during the idling period, the cutting away of the desired insole material, the return of the frame to initial position, the removal of the cut insole and the insertion of a 65 fresh insole. 70

The insertion of an insole to be cut requires the table 33 to be tilted downwardly to the dotted position shown in Fig. 1. During cutting the table 33 must be in the horizontal full line position of Fig. 1. To effect these positions auto- 75

5 matically at the desired relative times, the following expedient may be used. A link bar 95 is suitably pivoted to the under side of the table 33 as at 96. A second link bar 97 is pivotally attached to the free end of bar 95 at 98 and the free end of bar 97 pivotally supported at 99 to the frame 30. A third link bar 100 is pivotally attached to the common joint 98 of the two link bars 95 and 97. Link bar 100 at its free end is 10 forked and its tines 100' and 100² extend over the shaft 90. A cam following roller 101 is rotatably mounted at 102 to the link bar 100. This roller 101 is adapted to engage a cam 103 keyed to the driven shaft 90.

15 Cam 103 is so designed as to maintain the table 33 in horizontal position during the cutting and return strokes of the frame 50 and to tilt the table 32 to its aforesaid dotted position during a portion of the idling period of said frame. The 20 cut insole may thus be removed and a fresh insole inserted during the idling period. The two cams 91 and 103 in addition to being shaped individually to effect their respective functions are displaced radially with respect to each other on the shaft 25 90 to give a uniform single cycle action to the machine as a whole.

20 A tension spring 104 attached at its ends respectively to the crank lever 86 and to link bar 95 serves conveniently to maintain the cam following rollers 89 and 102 in contact with their respective cams.

30 It is desirable to clamp the insole material to the table 33 during the cutting operations. To effect this, a clamp bar 105 extending transversely of the table 33 is located rearwardly of the frame 50 and beyond the stroke limits of the latter. This clamp bar is supported at opposite ends by the vertical movable pins 106 which extend slidably through the table 33. The lower ends of 40 these pins have heads 107. Compression springs 108 are mounted around the pins between their heads and the underside of the table, tending thus to force the clamp bar 105 downwardly toward the top surface of the table 33. Members 45 109 supported rigidly from the frame 30 have lateral extensions 110 projecting into the paths of the respective heads 107 so that when the table 33 is tilted to its dotted position the pins 106 and the clamp bar are moved upwardly against the 50 action of the compression springs to permit the insertion of the insole material between the clamp bar and the top table face 32. When the table rises to horizontal position, the clamp bar 105 under the action of springs 108, effectively clamps 55 the insole material to said table 33.

55 Rotation of the shaft 90 may be controlled at will by the operator of the machine through a suitable clutch mechanism 115 controlled by a foot pedal lever 116, linkage 117 and operating lever 118. The clutch mechanism is of a well known type which operates to couple the driven shaft 90 to a drive shaft (not shown) in one position of the lever 118 and to uncouple said two shafts in another position of said lever.

60 Assuming that the position of the table 33 is that shown in dotted lines in Fig. 1, a rounded insole blank 12 is positioned on the table 33 with its heel and an edge of the shank portions resting against the guides 45 and 48 respectively. 70 Cam 103 on the driven shaft thereafter operates to raise the table to its full line horizontal position shown in Fig. 1 at which time the clamp bar effectively clamps the said insole blank against the table 33. Immediately thereafter, 75 the cam 91 operates to move the carriage frame

50 forwardly. As this occurs, the roller 70 rotates because of the engagement of the pinion 78 in the rack bar 79. As it rolls over the projection 40' of the die block 40, the central ball portion of the insole is pressed into the depression or 5 matrix 75 in the roller sufficiently to raise the plane of the lower face of the insole material in the ball portion above the plane of the upper face of the insole material. At the same time the outer portions 70' of the roller firmly press 10 the rand portion of the insole against the top of table 33. The cutting edge of the knife 65 moving with the carriage frame 50 directly behind the roller skives off the pressed up portion 16 of the insole as illustrated in Figs. 1a and 6, while 15 the balance of the insole is held down firmly as described completely severing this portion on completion of the forward carriage stroke, thus leaving a complete insole having a perforated ball portion in the form of a marginal rand 15 20 illustrated in Fig. 6. Upon completion of the forward stroke of the frame 50, the cam 91 causes quick return of said frame to its starting positions. Then the cam 103 moves the table 33 to its dotted position permitting removal of the cut 25 insole and the cut off part 16 and the insertion of a fresh uncut insole. Thereupon the cycle of operations described is repeated.

20 The adjustability of the guide member 45 permits the cutting of insoles for differently sized 30 shoes. The usual variation in length and breadth of insoles over a small range of sizes, for example, three or four length sizes and widths is not sufficient to require any change in the press roller 70 or the die block 40 since an adjustment of the 35 guide member 45 will compensate for the change of length of the insole. For other ranges of shoe sizes, differently sized die blocks 40 and press rollers 70 may be substituted to increase or decrease the size of the cut-out 16 from the ball 40 portion of the insole.

35 It is sometimes desirable to remove the central part of the ball portion of the insole in two pieces 16' and 16² as illustrated, for example, in Fig. 7 of the drawings. To effect removal in this manner with the apparatus of Figs. 1-3 inclusive, it is necessary to substitute a somewhat modified form of press roller and die block in the machine frame for the roller 70 and die block 40. The substitute die block 120 is illustrated in section in 50 Fig. 4 and in perspective in Fig. 4a. This die block 120 comprises a rectangular piece of metal or other suitable material shaped to fit the depression 38 in the table 33. The upper plane surface of the block is provided with an inverted 55 projection 121 which is V shaped in section and whose outline in plan corresponds substantially to the shape of the perforation P desired in the insole material. The angle of the V is preferably substantially obtuse at its apex. This projection 60 121 normally lies above the top surface of the table 33 when the die block is mounted in the depression 38.

65 The substitute press roller 125 which replaces press roller 70, is cylindrical and has a groove or matrix 126 developed on its cylindrical surface corresponding in shape to the projection 121 of the die block so that when the roller is rolled across the latter the projection 121 extends into the corresponding portion of the groove or matrix 126.

70 With the die block 120 and press roller 125 in place in the machine, operation of the latter is substantially similar to that already described. After a blank or rounded insole has been in- 75

serted, the table 33 rises to horizontal position and the frame 50 moves forwardly. As the roller moves over the insole and the die block 121, the insole is deformed in its ball portion as illustrated 5 in Fig. 4 and the knife skives or shears off the raised portions of the insole in the plane of the apex of projection 121 of the die block. This single cut results in a simultaneous separation from the ball portion of the two parts 16' and 10 16² shown in Fig. 7 leaving the insole with a 15 perforation P and marginal rand 15 identical with that of Fig. 6. This means for removing the insole ball portion in two pieces is of particular advantage when the insole material is 20 very thin and made of comparatively delicate or tearable material for the press roller not only presses firmly on the rand portion 15 of the insole during the cutting stroke but also on the central part of said ball portion at 125'. Thus 25 the insole is firmly held in place during the cutting operation and the danger of tearing is substantially eliminated.

Additional apparatus for effecting the cutting out of the insole in either of the ways of Figs. 6 30 or 7 is illustrated diagrammatically in Fig. 5. Herein, two superposed press rollers 131 and 132 are provided adjacent a table surface 133. Press roller 131 may be similar either to press roller 70 or press roller 125, having a groove 131' therein 35 similar either to the grooves or matrixes of the respective rollers 70 or 125. The second press roller 132 has a projection 132' developed thereon which corresponds in shape either to the projection 40' of the die block 40 or the projection 121 of the die block 120. The corresponding pairs of rollers are used in either event. A knife 135 whose cutting edge 136 is preferably positioned with its cutting edge tangent to the surface of the roller 131 and perpendicular to a plane including 40 both roller axes 134 and 134'. The insole material is fed from the table 133 through the bight between the rolls and temporarily deformed in the projections and grooves thereof, the deformed portion being sheared, spliced or skived off by the 45 knife immediately as the insole passes from the nip or bight of the rollers. If the grooves and projections on the rolls correspond to those of roll 70 and block 40, the insole material in the ball portion will be skived off in a single piece 16 as 50 shown in Fig. 6. On the other hand if the groove and projection on the rolls correspond to those of roll 125 and block 120, the insole material in the ball portion will be skived off in two pieces 16' and 16² as shown in Fig. 7.

55 It is to be noted that in every case the raised portions of the die block deform the insole during the cutting operation sufficiently to shift the plane of a portion of one surface thereof sufficiently above the plane of its other surface as to insure 60 the cutting through the entire thickness of the insole material in the ball portion leaving the perforation or opening P therein with the tapering walls terminating in the feather edge 15'. It is further to be noted that the knife edge cuts 65 through a plane intermediate the raised plane and the normal plane of the opposite surface and does not skive off any portion of the insole material other than that raised by the landed or raised portion of the dies. Furthermore, since 70 only thin stock is used for the insole, the cutting away is readily and quickly performed with the apparatuses described with a minimum of difficulty and wastage.

The general method of preparing a shoe embodying insoles cut in the apparatus above described and thin outsoles may comprise the following steps:

An insole 12 is applied to a preferably curved 5 or to a straight last (not shown) with the beveled portion of the perforation P facing upwardly, i. e. with the feather edge 15' flush with the last surface. An upper 10 and lining 11 is then lasted to the outwardly facing marginal portions of the 10 insole in its heel, and shank and to the rand portion 15 and the lasted upper 10 and lining 11 and trimmed to clear the perforation P and its tapered margins. The attachment of said upper and lining is either by suitable cement or by stitching to 15 the insole. Thereafter, the thin flat outsole 13 is cemented in place over and to the lasted upper and to the tapered marginal portion about perforation P in the insole which extends substantially parallel to the plane of the inner face of said out- 20 sole.

In the completed shoe, it will be noted, the outsole has only a small amount of curvature or may be substantially flat, while the insole at the 25 rand portion has a larger degree of curvature caused by the interposition of the upper and lining between the outsole and rand portion of the insole. The tapering inner edge of the rand portion, however, causes its feather edge 15' to lie 30 flush with the inner surface of the outsole so that the interior of the shoe is substantially smooth and free of ridges, welts or the like.

Since the major part of the ball portion has been cut away as described, only the thickness of 35 the outsole which is of thin material is present in the major part of the shoe ball portion. The latter thus is more flexible than those portions of the shank and heel which include the double thickness of both insole and outsole. The finished shoe has all the desired characteristics 40 described herein, is economical to manufacture, and superior, from the point of view of flexibility, to shoes having complementary interfitting parts in their ball portions.

While I have described preferred embodiments 45 of my invention, it is to be understood that various modifications thereof are contemplated within the scope of the appended claim. I do not, therefore, wish to be limited to the exact details described and shown.

I claim:

That improvement in the method of preparing insoles for shoes which comprises providing a single thin sheet of original insole stock shaped to insole form and including a forepart portion, 55 deforming said sheet in said forepart portion intermediate its outer edges in such manner as to form ridges in said forepart portion which have V-section and to such extent that points on the face of one surface plane of said sheet are shifted 60 transversely beyond the normal surface plane of the opposite face of said sheet, and while maintaining such deformation, cutting said sheet along a plane intermediate said normal surface plane and the said shifted points whereby said sheet is cut through its entire thickness in said forepart portion and divided into three pieces 65 thereat, one of which pieces comprises said insole form with its forepart portion having an opening defined by a rand having tapering inner margins 70 terminating in a feather edge bordering said opening.

FRED MACCARONE.
